UNITED STATES PATENT OFFICE.

FRANZ K. KRAG, OF CHICAGO, ILLINOIS.

POWDER BOX.

Application filed January 14, 1925. Serial No. 2,245.

This invention relates to powder boxes used for the purpose of holding and delivering powder for cosmetic purposes. It has for one of its objects an improvement in the 5 type of powder box which is disclosed by my patent application, Serial No. 757,992, filed Dec. 26, 1924, and the improvements relate to the means by which the powder is delivered for use by the box.

10 Of the accompanying drawings Fig. 1 is a plan view of the box with the cover raised; Fig. 2 is a central vertical sectional view of the box with the cover closed; Fig. 3 is a corresponding partial section at 90° from 15 the section of Fig. 2; Fig. 4 is a bottom view of one of the powder delivering elements; and Fig. 5 is a plan view of a resilient member used in the box.

The powder box to which my improvement 20 relates comprises a bottom compartment 6. This compartment is preferably cylindrical and comprises a bottom 7 and annular sides 8. Mounted in this bottom compartment is a central compartment having annular sides 25 9, a perforated fixed top 10, a perforated rotatable disk top 11, and a false or slidable bottom 12. Pivoted to the central compartment, by means of a hinge 13, is a top compartment comprising the cover 14 and 30 a mirror 15 mounted therein. The false bottom 12 is adapted to support the powder 16 which is inserted in the central compartment between the false bottom, and the disk 11. Beneath the false bottom the resilient 35 means Fig. 5 are provided for pressing the powder which rests on the false bottom against the disk 11.

The disk 11 is provided with a series of 40 holes 17. This disk is preferably pivoted to the top 10 in any suitable manner, such as by means of a pivot 18, and the disk has flanges 19 projecting upwardly through slots 20 in the top of the central compartment. Hence, when the cover 14 is raised, 45 the disk can be rotated by means of these flanges 19; and when so rotated the powder will work upwardly into the openings 17, because of the pressure on the false bottom of the resilient member 21.

50 This cover 10 has a series of holes 22 which are so arranged as to register with

the holes 17 when the disk 11 is turned to certain positions. For instance certain openings 17 will register with certain openings 22 when the disk is turned slightly 55 clockwise, and other openings will register as the disk is turned further, and when turned clockwise as far as possible each of the openings 17 will register with an opening 22. When any two of the openings 60 register the powder will pass out of the upper opening on to the upper surface of the top 10, and may be then applied to the powder puff in the usual manner. So that by 65 rotating the disk first in one direction and then in the other as much powder may be delivered onto the top of the central compartment as is desired. But when the disk is rotated so that the flanges 19 are in the 70 central portion of the slots 20, none of the holes will register, and the powder cannot 75 pass out from the central compartment. In order to prevent a tendency of the powder to pack between the peripheral portions of the false bottom and the disk 11 the under surface of the disk may be roughened in some manner, such as by means of ribs 24 pressed thereon.

Any suitable resilient means may be used 80 for pressing the false bottom towards the disk. I prefer for the purpose the means illustrated in Fig. 5 which comprises a strap 25 which is normally slightly longer than the inner diameter of the bottom part of the bottom compartment 6 so that when the 85 strap is placed in the bottom of this compartment the ends 26 will press against the inner wall of the annular groove 27 and the strap will be held from rotation. Fixed to this strap in any suitable manner is a resilient member 28, having a central bar 29 which is bowed upwardly and fixed in any 90 suitable manner to the false bottom. This member 28 also has side bars 30 which are bowed downwardly and which are fixed to 95 the strap 25, preferably by means of flanges 31 passing up from the bar 25 into notches 32 in the bars 30. In this manner the false bottom is held from rotation and this bottom together with the resilient member may 100 be at any time very conveniently removed from the box.

I claim as my invention:

A powder box comprising a top having perforations therethrough, a false bottom movably mounted in said box beneath said top, a fixed bottom in said box, and resilient means mounted between said bottoms, said means comprising a strap non-rotatably

mounted on said bottom, and resilient means fixed to said strap; said resilient means comprising a strip fixed to said bottom and a second strip fixed to said strap. 10

In testimony whereof, I hereunto set my hand.

FRANZ K. KRAG.
